CARL EKBERG, OF NEW YORK, N. Y., ASSIGNOR OF ONE-HALF TO AUGUST W. ANDERSON,
OF NEW YORK, N. Y.

SAFETY GAS-COCK.

1,181,512.

Specification of Letters Patent. Patented May 2, 1916.

Application filed November 5, 1915. Serial No. 59,787.

To all whom it may concern:

Be it known that I, CARL EKBERG, a citizen of the United States, and a resident of New York, in the county and State of New York, have invented a certain new and useful Safety Gas-Cock, of which the following is a specification, the same being a full, clear, and exact description of the invention, such as will enable others skilled in the art to which it appertains to make and use the same.

This invention relates to devices employed in the distribution and consumption of illuminating elastic or other fluid mediums, and in particular to a cock or turn-valve for the purpose of permitting or arresting the flow of gas through the same, whereby a predetermined small quantity of the elastic fluid may be allowed to pass therethrough, or the passageway may be enlarged to provide a variety of predetermined larger capacities, and whereby the said device may become automatically locked in either of the said plurality of open or "on" positions, and also held automatically locked when in a closed or "off" relation.

To attain the desired end, the invention consists in the construction, arrangement and operation of parts hereinafter set forth. In the drawings which accompany and form a part of this invention, and illustrative of one embodiment of the same, Figure 1 is a view in longitudinal section of an article constructed according to my invention; Fig. 2 is an elevation of the same; and Fig. 3 is a plan view, the operating key being removed.

Like numerals of reference indicate like parts in all the views. Referring to the drawings by numerals, 1 denotes the socket member of the gas-cock, the respective ends of which may be attached to a gas supply pipe and to a plug on a gas bracket arm or other fluid container in the usual or any suitable and approved manner. The socket member is made with the usual passageway 19 and a conical valve seat 2, at the larger portion of which are preferably formed an alined series of engaging devices, as circumferential recesses or notches 3, 4, 5, 6 and 7, the notches 5 and

6 having an inclined side wall and the notches 3, 4 and 7 being radially disposed. The socket is also made with a stop pin 8 located adjacent to the valve seat. In the other part of the socket there is ordinarily located a recess 9.

The conical portion of the plug-valve member 10 is formed with the usual horizontal port 18, the smaller end of the plug 60 preferably extending up through the recess 9 and working in a bearing at the top of the socket to which it is secured in a movable relation by any suitable means, as by a nut. A coiled spring 11 is ordinarily located in the recess 9, the extremities of which are preferably respectively secured to the wall of the said recess and to the plug-valve. The other end of the plug terminates in an operating key 12 in which are mounted a plurality of engaging devices, as two yielding stop-fingers 13 and 14 preferably held in a normal outward and resilient relation, as by an intermediate spring 15, and ordinarily pivoted at or near the outer end of the operating key, as by the pintle 16.

The pressure stop-fingers are preferably made so as to register with and simultaneously respectively engage the notches 3 and 4, while the finger 14 is preferably constructed and arranged to register with and engage the notches 6 and 7 during the operation of the device; and the finger 13 will, in use, preferably register with and engage the notch 5, all of which notches lie in the path of the stop fingers. The plug-valve is also made with a stop device, as a screw or lug 17 constructed and arranged to engage and abut the pin 8 when the device is in a closed relation, the said parts being normally held in contact by the spring 11.

In operation, the parts are normally held in a closed relation as illustrated in Fig. 1, the finger 13 being in the notch 3, and the finger 14 being in the notch 4. In order to unlock and open the cock, the stop-fingers 13 and 14 are pressed inwardly or toward each other, which movement releases the stop-fingers from the socket member. The said fingers will now, as the operating key 100 is turned, ride along the inside of the casting of the socket until the finger 14 enters

the notch 6, at which time the cock will be partly opened and a small flame may be had, the plug-valve being now locked from rearward movement. By now merely turning the operating key farther around, without applying pressure to the fingers, the latter will ride farther along the casing until the finger 14 rides out of the beveled or inclined side wall of the notch 6 and the finger 13 enters the notch 5, when the cock will be still more open, as for example in a half open position, and the gas will burn with a larger flame, the plug-valve being now again locked from rearward movement. By a continued forward movement of the operating key, the finger 13 will ride out of the beveled or inclined side wall of the notch 5, and the finger 14 will enter the notch 7, at which point the cock will be locked in a full open position, and the operating key cannot be turned in either direction unless both of the stop-fingers are pressed inwardly. In order to close the cock when in either of the said three open positions, it is merely necessary to press the spring stop-fingers 13 and 14 toward each other, whereupon the spring 11 will carry the plug-valve 10 in a rearward direction until its movement is stopped by the engagement of the pin 8 with the lug 17.

It will thus be seen that by the employment of a socket member having a series of aligned notches in combination with a plug-valve member having pressure fingers which may be selectively engaged with the said notches, a very efficient, safe and durable device is obtained. In the course of the rearward movement of the plug-valve, the fingers will consecutively engage with the notches, so that, if the pressure on the fingers is released, the valve will be held in a partly open position, rearward movement of the same being prevented (to avoid accidental turning out of the smallest flame) until the fingers are again forced inwardly, whereupon the device will become automatically locked in a closed relation.

It is obvious that the invention may be employed in connection with fluids and mediums other than the preferred one mentioned herein, the invention residing in the peculiar construction and arrangement of parts which may be employed in connection with any medium with which the same may be found to be adapted to be used.

I wish it to be understood that I do not desire to be limited to the exact details of construction shown and described, for obvious modifications will occur to persons skilled in the art.

What I claim as my invention is:—

1. In a device of the class described, a socket member having a series of engaging devices, in combination with a plug-

valve member having pressure fingers to selectively engage the said engaging devices, means to lock the pressure fingers so that the plug will be in an open relation, and also means comprising a torsion spring, upon manipulating the said fingers, to automatically rotate the plug valve to bring it to a closed locked position. 70

2. In a device of the class described, a socket member having a series of aligned engaging devices, in combination with a plug-valve member having pressure fingers to selectively engage the said engaging devices, and also with means to hold the plug-valve in either one of a plurality of open positions so as to prevent the rearward movement thereof in combination with a torsion spring to rotate the plug when in an open position upon the release of the locking fingers. 75

3. In a device of the class described, a socket member having a series of aligned engaging devices, in combination with a plug-valve member having pressure fingers adapted to simultaneously engage some of the said engaging devices and to alternately engage the remainder of the same in combination with a torsion spring to rotate the plug when in an open position upon the release of the locking fingers. 80

4. In a device of the class described, a socket member having a series of aligned engaging devices, in combination with a plug-valve member having pressure fingers adapted to simultaneously engage some of the said engaging devices so as to be locked from either forward or rearward movement, and to alternately engage the remainder of the same so as to prevent rearward movement thereof in combination with a torsion spring to rotate the plug when in an open position upon the release of the locking fingers. 90

5. In a device of the class described, a socket member having a series of engaging devices, in combination with a plug-valve member having pressure fingers adapted to engage the said engaging devices, and with means to automatically lock the said fingers so that the plug will be in an open relation, and also to automatically lock the said fingers so that the plug will be in a closed relation, in combination with a torsion spring to rotate the plug when in an open position upon the release of the locking fingers. 110

6. In a device of the class described, a socket member having a series of aligned engaging devices, in combination with a plug-valve member having pressure fingers adapted to selectively engage the said engaging devices, and with means to automatically lock the said fingers so that the plug will be in an open relation, and also to stop the fingers in a plurality of positions in 115 120 125

their rearward movement and to automatically lock the said fingers so that the plug will be in a closed relation in combination with a torsion spring to rotate the plug when in an open position upon the release of the locking fingers.

In testimony of the foregoing specifica-

Copies of this patent may be obtained for five cents each, by addressing the "Commissioner of Patents,
